SELF-GRINDING VALVE

Oscar Joel Ostlind, Marshfield, Oreg.

Application August 11, 1933, Serial No. 684,670

7 Claims. (Cl. 251—129)

My invention relates to devices containing a movable valve and a fixed valve seat, of the type known as check valves and in which it is desirable in order to maintain the fluid tightness of the 5 valve to rotate the valve somewhat with respect to its seat each time it operates.

Such rotation has two beneficial results; the valve rests upon its seat in a different place at each time and theoretically if it can be made to 10 rotate just as it closes, a slight grinding action of the valve with respect to its seat each time the valve closes will permanently keep both elements in the condition of a freshly ground valve and valve seat.

15 The idea of doing this is not new. Many attempts have been heretofore made to cause this rotation and self-grinding action and a considerable number of patents have been taken out, all of which use some type of propeller in connection 20 with the valve to give the valve the desired rotation and in all of them that this inventor is familiar with the vanes of the propeller are above, or below the valve and spaced some distance from it and some are provided with propellers both 25 above and below, so that the shielding action of the valve itself may not prevent the liquid flow from influencing the propeller to rotate the valve.

The result of all this is that the valve rotates 30 freely when wide open when such rotation will not accomplish any useful purpose since the valve is then a long way from its seat, and it will fail to rotate just as the valve leaves its seat and just 35 as it closes when that is the only period during the operation in which such rotation can have any self-grinding effect.

The object of this invention is to provide a 40 structure that will eliminate the difficulties mentioned above and to produce a valve so arranged with respect to its seat and adjacent structures that it will have a decided rotary motion just at the instant that it leaves its seat and for a short 45 distance above its seat as it opens to full capacity, that will be beyond the influence of any rotative effect after opening to full capacity, and that will then come under the influence of currents tending to rotate the valve with respect to its seat just prior to and during the closing action. 50 With the above stated objects in view and other advantages which will appear from the subjoined specification, the invention resides in the structures, elements and combinations of elements delineated in the drawing and hereinafter described in the specification and claimed in the 55 claims.

In the drawing.—

Fig. I represents an embodiment of my new invention in the form of a vertical check valve, though the outward shape of the body is not important and it is not intended to limit the invention to a valve of this type; it may be made in the globe or angle valve form with equal facility:

Fig. II is a section of Fig. I.

In the drawing a valve body 3, is shown to be 65 made in two parts with a joint at 3a and a liquid inflow at 4, with an outflow at 5, which may be threaded or flanged or otherwise arranged in any convenient manner.

Within the valve body 3, is a valve seat 6, and 70 a cooperating valve 7, shown here to have a guide stem 8, working within a guide 9, with a stop collar 10. Different types of valve guides may be provided. Mounted directly upon the top of the valve 7 and rigid therewith is a propeller 11, 75 which is composed of a plurality of vanes as shown in Fig. II and any convenient arrangement of the number of the vanes and their shape may be adapted since propellers of all kinds are old and well-known.

Immediately adjacent the discharge edge of the valve seat 6, at the point marked 6a of the discharge edge of the valve 7, marked 7a, is a reversing chamber 12, which constitutes the main contribution to the art to be found in this invention.

In Fig. I the valve is shown slightly raised from its seat as it will be when just opening and just before it closes and fluid flowing upward through the valve from 4 in the direction of 5 and passing 90 between the valve and seat will, under the influence of this reverse chamber 12, take the direction indicated by the arrows in Fig. I, that is to say, directly against the vanes of the propeller 11, causing a positive rotation of the propeller 11, and the valve 7, with respect to the valve seat 6. As the valve opens further it is apparent that as soon as the propeller 11 passes beyond the discharge lip 14, the propeller 11 will 95 no longer be under the influence of upwardly 100 passing fluid since it will be entirely shielded by the valve 7 and no rotation will take place.

As the flow slacks due to controlling a master valve, stopping of a pump, or in any other manner, the valve 7 will settle toward its seat 6 and the 105 propeller will be back under the influence of the reversing chamber 12 and the last end of the flow through the valve, and again assume the direction of rotation indicated by the arrow in Fig. II; and this rotative movement of the valve 7 which 110

will contact its seat while running will not only insure a different seating position each time the valve operates but will insure the self-grinding so long sought but never attained to the degree of perfection possible with my new combination of a reversing chamber and a propeller. Variations in size of the propeller with respect to the diameter of the valve; variations in size of the reversing ring and its depth may be made to suit various conditions of operation. The arrangement of the vanes or propeller may follow any of the numerous designs well-known in the propeller art without departing from the principle of my new invention, which, having disclosed so that anyone familiar with the art to which it appertains can make and use it, what I claim as new and desire to secure by Letters Patent, is—

1. A self-grinding valve, defined in part as a valve seat, a co-operating valve, propeller vanes superposed and rigid with the valve and a reversing chamber positioned to surround the valve at its discharge edge, whereby liquid flow through the valve is directed against the propeller vanes.

2. In a self-grinding valve, a valve seat, a co-operating valve, guide members for the valve, propeller vanes superposed on said valve and rigid therewith and a curved reversing ring positioned adjacent the discharge edges of the valve and seat that is adapted to direct flow through the valve against the said propeller vanes when the valve is partly open.

3. In a self-grinding valve, the combination of a valve and valve-seat, a propeller positioned above the valve and rigid therewith of such di-

ameter that it will be substantially shielded by the valve from influence by straight flow and a reversing chamber surrounding the discharge edge of the said valve-seat that is adapted to direct current flow against the said propeller when the valve is partly opened.

4. In a self-grinding valve, a valve seat, a valve on said seat that is adapted to open under the influence of flow, a propeller superposed on said valve and shielded by the same and a reversing ring for flow through said valve that directs flow against the propeller when the valve is adjacent but not touching its seat.

5. In a check valve the combination of a valve, a seat for said valve, a reversing chamber positioned adjacent the discharge edges of said valve and seat and a propeller superposed on said valve positioned to be revolved under the influence of currents from said reversing chamber to rotate said valve on its seat.

6. In a check valve the combination of a valve, a seat for said valve, a reversing chamber positioned adjacent the discharge edges of said valve and seat and propeller vanes positioned to be revolved under the influence of currents from said reversing chamber to rotate said valve with respect to its seat.

7. In a check valve, the combination of a valve, a seat for said valve, a reversing chamber adjacent the discharge edges of said valve and seat and vanes rigid with said valve adapted to cause said valve to rotate under influence of currents directed from said reversing chamber.
